ERNEST H. HOLZWORTH, OF LOWELLVILLE, OHIO.

SLAG-POCKET FOR FURNACES.

1,200,839.

Specification of Letters Patent.

Patented Oct. 10, 1916.

Application filed March 16, 1916. Serial No. 84,618.

To all whom it may concern:

Be it known that I, ERNEST H. HOLZWORTH, a citizen of the United States, residing at Lowellville, in the county of Mahoning and State of Ohio, have invented new and useful Improvements in Slag-Pockets for Furnaces, of which the following is a specification.

My invention relates to slag-pockets for metallurgical furnaces and more particularly for pockets of the open hearth regenerative type.

In the usual operation of an open hearth furnace for manufacturing steel, the filling of the slag-pockets with slag necessitates the occasional stopping of the operation of the furnace for cleaning out the pocket. This cleaning of the slag-pockets is destructive of the brickwork of which they are made, and causes a large expense for rebuilding the pockets and a large loss in the output of the furnace.

It is one of the objects of this invention to divide each slag pocket into sections or subpockets, so that the slag therein may be in relatively small masses which may be removed by a crane without waiting for the mass of slag to get cold.

Another object is to line the slag-pocket with false relatively fragile walls which will break up when the crane is applied to lift the slag, and thereby prevent the destruction of the expensive fixed walls which surround the pocket and support the superstructure at the end of the furnace.

A still further object is to provide crane-engaging devices which project into or across the subpockets when empty so that when the subpockets have been filled with slag, the latter may as soon as solidified be quickly removed.

Further objects will appear hereinafter.

Referring to the accompanying drawing, Figure 1 is a vertical section showing two slag-pockets and the adjacent portions of a furnace; Fig. 2, a horizontal section on the line II-II, Fig. 1; and Fig. 3, a plan view, partly broken away, showing one of the crane-engaging devices.

On the drawing, 1 and 2 show two parallel adjacent slag-pockets, but as the construction of both slag-pockets is the same, I will describe but one, that marked 1. This pocket has the usual side and end walls 3. On the bottom of the pocket I put a mixture 4 of dolomite and wood, on which I con-

struct a series of subpockets 5, each having the bottom 6, side walls 7, and the end walls 8 made of refractory brick or other suitable material. The opposing or inner faces 60 of the walls 7 are preferably vertical and parallel, while their outer faces preferably diverge downwardly without engaging with the side walls 3. The adjacent ends of the successive subpockets are spaced apart a 65 short distance, and the end wall 8 of the rearmost subpocket is also spaced a short distance from the adjacent wall 3. The said spaces between the side walls 7 and the walls 3, between the end walls of successive subpockets, and between the end wall of the rear 70 subpocket and the wall 3, are filled with the said mixture 4 of dolomite and wood. The said mixture 4 extends up preferably slightly above the top of the walls 7, the 75 upper surface thereof having a brick covering 9 inclined toward the subpocket, so that any slag falling thereon will flow into the subpocket. It is thus seen that the subpockets may be regarded as being separated 80 by partitions composed of a pair of walls 8 separated by a filler of the mixture 4.

Each of the subpockets has one end provided with at least one crane-engaging device 10 which I have shown in the form of 85 an elongated metal link interlinked with a similar link or a crane-engaging device 11 extending transversely through each subpocket and having its ends extending into the mixture 4. These crane-engaging devices 10 and 11 may be arranged at any suitable level in the subpockets so that the slag which collects therein may rise above their level. I have shown these devices at about half the distance between the top and the 90 bottom of the subpockets. The outer end of each device 10 is supported in the partition between the ends of adjacent subpockets, except that the device 10 of the outermost subpocket 5 extends through the wall 8 merely, 95 which ordinarily will not be accompanied with the mixture 4 of dolomite and wood. This device 11, as well as that marked 10, may be provided with a coating 12 of fire-clay, ganister, or other refractory material 105 which will cling to the iron, steel or other material of which the devices 10 and 11 may be composed.

In Figs. 1 and 2 I have shown one subpocket filled with a mass 13 of slag in which 110 are embedded those portions of the crane-engaging devices 10 and 11 which are in

the pocket. When the subpockets have become filled with slag to the top of the subpockets or well above the devices 10 and 11, a crane-hook is connected to the eye of the device 10 which projects outside of the end wall 8. Owing to the heat from the slag and the hot gases passing over the pockets, the wood in the mixture 4 will be converted into charcoal which is a very brittle substance. When the crane pulls up on the device 10 the entire mass of slag in the end-most subpocket 5 should be readily lifted out of its place, the charcoal and dolomite readily breaking up. Also during the operation the walls 7 and 8 of the subpocket will be more or less broken up and removed. After the slag from the first subpocket has been removed, the crane-hook will be connected to the device 10 of the next subpocket and the operation continued until all the slag in the several subpockets has been cleared away. In case it is found impossible to lift a mass of slag, the charcoal and dolomite at the sides of the subpocket may be readily cleared away down to the device 11, whereupon crane-hooks may be connected to the eyes of the said device 11 and the said subpocket loosened. The slag may then be removed by the continued application of the crane to the device 11 or the crane may be disconnected from the said device and again connected to the device 10.

The mixture 4 is composed of dolomite or other refractory substance broken into small pieces intermingled with pieces of wood which may be in any form, such as blocks or long strips or poles. It is not essential that this mixture shall be made of any particular material so long as it shall become or remain in a relatively fragile condition, whereby it may be broken up by the lifting action of the crane or by a tool employed in gaining access to the ends of the said device 11 as above described.

I do not limit myself to the precise form of crane-engaging devices shown or to any definite number of them. It may not be necessary to use both the devices 10 and 11 but I prefer to use both of them, or at least that the devices 10 shall be interlinked with a cross-piece preferably such as shown by the devices 11 so that there will be no danger of the devices 10 pulling out of the slag.

I claim—

55. 1. In a slag-pocket, fixed side walls, a plurality of subpockets arranged end to end between the side walls, crane-engaging devices having portions arranged within the subpockets so as to be inclosed by the slag, and a readily displaceable filler between the side walls and the subpockets.

2. In a slag-pocket, fixed side walls, a plurality of subpockets arranged end to end between the side walls, crane-engaging devices having portions arranged within the

subpockets so as to be inclosed by the slag, and a readily displaceable filler between the side walls and the subpockets and also between the ends of successive subpockets.

3. In a slag-pocket, fixed side walls, a plurality of subpockets arranged end to end between the side walls, crane-engaging devices having portions arranged within the subpockets so as to be inclosed by the slag, and a readily displaceable filler between the side walls and the subpockets, the said filler containing a carbonaceous material convertible into charcoal by the heat of the furnace gases and the slag.

4. In a slag-pocket, fixed side walls, a plurality of subpockets arranged end to end between the side walls, crane-engaging devices having portions arranged within the subpockets so as to be inclosed by the slag, and a readily displaceable filler between the side walls and the subpockets, the said filler containing a mixture of refractory bodies and a carbonaceous material convertible into charcoal.

5. In a slag-pocket, fixed side walls, a plurality of subpockets arranged end to end between the side walls, crane-engaging devices having portions arranged within the subpockets so as to be inclosed by the slag, and a readily displaceable filler between the side walls and the subpockets, and also beneath the subpockets.

6. A plurality of slag-pockets arranged end to end, and metallic devices having portions within the path of the slag as it fills the pockets and crane-engaging portions out of the path of the slag.

7. A plurality of slag-pockets arranged end to end, metallic devices having portions within the path of the slag as it fills the pockets and crane-engaging portions out of the path of the slag, and refractory material on the portion of the said devices within the pockets.

8. A plurality of slag-pockets arranged end to end, metallic devices having portions within the path of the slag as it fills the pockets and crane-engaging portions out of the path of the slag, refractory material on the portion of the said devices within the pockets, the metallic device of one end pocket being accessible, and the metallic devices of the remaining pockets becoming accessible as the slag-pockets with the contained slag are successively removed.

9. A plurality of slag-pockets arranged end to end, and metallic devices having portions with the path of the slag as it fills the pockets and crane-engaging portions out of the path of the slag, the said devices comprising flattened endless links, arranged lengthwise of the pockets.

10. A plurality of slag-pockets arranged end to end, and metallic devices having portions within the path of the slag as it fills

the pockets and crane-engaging portions out of the path of the slag, the said devices comprising a pair of flattened interlinked links for each pocket, one arranged lengthwise of the pocket and the other transversely thereof.

11. A plurality of slag-pockets arranged end to end, metallic devices having portions within the path of the slag as it fills the pockets and crane-engaging portions out of the path of the slag, and a metal anchor for anchoring the said devices in slag in the pockets.

12. In a slag-pocket, fixed side walls, a plurality of subpockets arranged end to end between the side walls and a readily displaceable filler between the side walls and the subpockets and also between the ends of successive subpockets.

13. In a slag-pocket, fixed side walls, a plurality of subpockets arranged end to end between the side walls, and a readily displaceable filler between the side walls and the subpockets, the said filler containing a carbonaceous material convertible into charcoal by the heat of the furnace gases and the slag.

14. In a slag-pocket, fixed side walls, a plurality of subpockets arranged end to end between the side walls, and a readily displaceable filler between the side walls and the subpockets, the said filler containing a

mixture of refractory bodies and a carbonaceous material convertible into charcoal.

15. In a slag-pocket, fixed side walls, a plurality of subpockets arranged end to end between the side walls, and a readily displaceable filler between the side walls and the subpockets, and also beneath the subpockets.

16. In a slag-pocket, fixed side walls, and a plurality of subpockets arranged close together between the side walls, the sides of the subpockets being composed of temporary walls and the divisions between adjacent subpockets being also composed of temporary walls.

17. In a slag-pocket, fixed side walls, a plurality of subpockets within the same, having temporary side walls and separated by temporary partitions, and readily removable filler between the adjacent fixed and temporary side walls.

18. In a slag-pocket, fixed side walls, a plurality of subpockets within the same, having temporary side walls and separated by temporary partitions, and readily removable filler between the adjacent fixed and temporary side walls and also in the partitions.

Signed at Pittsburgh, Pa., this 13th day of March, A. D. 1916.

ERNEST H. HOLZWORTH.
